MODE TRANSFORMER

Seymour B. Cohn, Flushing, N. Y., assignor to Sperry Rand Corporation, a corporation of Delaware

Application October 24, 1950, Serial No. 191,849

11 Claims. (Cl. 333—21)

The present invention relates generally to ultra-high frequency apparatus, and in particular to a mode transformer for transforming a TE₁₀ mode in a rectangular waveguide to a circularly polarized TE₁₁ mode in an axially aligned circular waveguide.

In many types of ultra-high frequency equipment it is desirable to couple a rectangular waveguide to a circular waveguide. In such coupling it is frequently desired that the mode of transmission in the rectangular guide be TE₁₀ and the mode in the circular guide be the TE₁₁ mode. Copending application S. N. 234,124, filed June 28, 1951, describes such a structure wherein the axis of the rectangular guide is at right angles to the circular waveguide. The present invention describes a structure wherein the same electrical result obtains, but the rectangular waveguide and the circular guide are in axial alignment.

It is, therefore, an object of the present invention to provide a mode transformer for coupling a rectangular waveguide to a circular waveguide in which the two guides are in axial alignment.

It is a further object of the present invention to provide a mode transformer for coupling the TE₁₀ mode in a rectangular waveguide to a circularly polarized wave of the TE₁₁ mode in a circular waveguide.

It is still a further object of the present invention to provide an axially aligned mode transformer which operates over a relatively broad range of frequencies.

These and other objects will become more apparent and a better understanding of the invention will result from a consideration of the drawings in which:

Fig. 1 is a perspective view partially in section of one embodiment of the present invention.

Fig. 2 is a diagrammatic sketch of the device shown in Fig. 1 useful in explaining its operation.

Fig. 3 is a section view of a modification of the device shown in Fig. 1, and

Figs. 4—6 are perspective views partially in section of further embodiments of the present invention.

Referring now more particularly to Fig. 1, there is shown a section of rectangular waveguide 10 having a width *a* and a height *b*. Rectangular waveguide section 10 abuts end plate 11 of circular waveguide section 12, and is permanently joined thereto, the two waveguide sections being axially aligned.

A coaxial line section 15 is supported at the junction of rectangular waveguide section 10 and circular waveguide section 12, and is oriented along the common axis 16 of the two waveguide sections. This coaxial section 15 may be supported in a number of ways, for example, by a dielectric support 17. One end of coaxial line section 15 terminates within rectangular waveguide section 10 and the other end terminates within circular waveguide section 12.

Mounted at each end of coaxial line section 15 is a pickup unit. In Fig. 1, these pickup units are shown as dipoles, although any other similar energy pickup unit may be utilized. Dipole 20, which is mounted at that end of coaxial line section 15 which terminates in rectangular

2

waveguide section 10, is oriented with its axis parallel to the shorter dimension of the waveguide cross section. That is, dipole 20 is so positioned to be excited by the electric vector of the dominant mode TE₁₀ in the rectangular waveguide section 10.

Dipole 25, which is mounted at that end of coaxial line section 15 which terminates within circular waveguide section 12, is oriented at right angles to dipole 20. That is, the axis of dipole 25 lies along a diameter of circular waveguide section 12 which is parallel to the large dimension of the cross-section of rectangular waveguide section 10.

In operation, energy is transmitted along rectangular waveguide section 10 in the TE₁₀ mode. The electric vector, shown diagrammatically as E₁ in Fig. 1, excites dipole 20. As a result, energy is transmitted along coaxial line section 15 and is radiated into circular waveguide by dipole 25. Because of the orientation of dipole 25, the radiated energy has its electric vector at right angles to E₁ as is indicated by vector E₃.

Since rectangular waveguide section 10 is directly coupled to circular waveguide section 12 energy will also be coupled directly thereto. The electric vector of this directly coupled energy will, of course, be parallel to the electric vector E₁. This is represented by vector E₂.

It is immediately seen that the physical orientation of the two electric vectors of the energy coupled from rectangular waveguide section 10 to circular waveguide section 12 is one of right angles; that is, they are physically 90° apart in space.

By adjusting the length L of the coaxial line section properly, the electrical orientation of vectors E₂ and E₃ can be made to be 90° apart in phase. Thus it is seen that there are established in the circular waveguide section 12 two waves of the TE₁₁ mode that are spaced 90° apart electrically and physically, so that the resultant is a circularly polarized wave of the TE₁₁ mode.

Fig. 2 illustrates this effect in somewhat greater detail. The energy passing through the rectangular waveguide section 10 is in the TE₁₀ mode. This energy excites pickup unit 20. In addition, it travels a distance *l*₁ farther in waveguide section 10. In so doing, it suffers a phase shift, ϕ_1 , which is equal to

$$\frac{2\pi l_1}{\lambda g_1}$$

where λg_1 is the wavelength within guide 10.

The energy induced in coaxial line section 15 travels in a TEM mode and suffers a phase shift, ϕ_3 , which is equal

50 to

$$\frac{2\pi L}{\lambda} \sqrt{K_3}$$

where K_3 is the dielectric constant of the coaxial line section 15 and λ is the freespace wavelength of the energy.

The energy which is directly coupled into the circular waveguide section 12 travels a distance *l*₂ before passing dipole 25. This energy is in the TE₁₁ mode and suffers a phase shift, ϕ_2 , which is equal to

$$\frac{2\pi l_2}{\lambda g_2}$$

where λg_2 is the wavelength within guide 12.

Therefore, all that is necessary in order to insure E₂ and E₃ of being in time quadrature is that the following relationship obtain:

$$\phi_1 + \phi_2 + \phi_4 + \frac{(2n+1)\pi}{4} = \phi_3$$

70 where *n*=zero or any $\pm$ integer, and ϕ_4 is a phase shift approximately independent of *l*₁ and *l*₂ which lumps to-

gether the individual phase shifts at the dipoles and at the junction of waveguides 10 and 12.

Since λ_{g1} and λ_{g2} vary because of the different guide section and their resulting mode differences, it is possible to maintain the overall length of coaxial line section 15 constant and vary the ratio l_1/l_2 and thus adjust the device to operate over a range of frequencies. Such a structure is shown in Fig. 3. In this figure, coaxial line section 15 is supported on a dielectric slide 30 which passes through a wall of rectangular waveguide section 10. By adjusting the longitudinal position of slide 30, the ratio of l_1 to l_2 may be varied. This changes ϕ_1 and ϕ_2 , so that the desired 90° phase shift occurs at a selected operating frequency.

As stated above, the invention is not intended to be limited to the use of dipoles as pickup units, but other forms such as loops and probes may be used with equal facility. The only requirement in the type used is that the pickup unit inserted in the rectangular guide be excited by the regular TE₁₀ mode, and that the pickup unit in the circular guide excite a TE₁₁ mode having a plane of polarization which is at right angles to the electric vector of the TE₁₀ mode.

In addition, the invention is in no way limited to coaxial line for coupling. Instead a two wire transmission line may also be utilized.

It should further be pointed out that, although the operation of the device is described as transforming energy from the TE₁₀ mode in the rectangular guide to a circularly polarized wave of the TE₁₁ mode in the circular guide, the structure will also operate in the reverse direction. In Fig. 1, dipole 25 will be excited by the horizontal component of an incident circularly polarized wave, which will enable dipole 20 to excite a TE₁₀ mode in rectangular guide 10.

In some cases, it may be necessary to minimize phase shifts due to the discontinuity of the two wave guide sections. Another embodiment of the present invention is shown in Fig. 4. In this embodiment rectangular guide section 40 which in turn couples to circular guide section 12. By using such an intermediate guide section 40, the effect of the discontinuities may be reduced. Knob 41 is utilized to adjust the position of coaxial wave guide section 15, longitudinally as before.

In order to further reduce the discontinuities, a taper section could be applied between rectangular wave guide section 10 and rectangular wave guide section 40. This embodiment is illustrated in Fig. 5, with taper section 50 inserted.

Fig. 6 shows a further modification in which a flared section 60 is inserted between rectangular wave guide section 10 and circular wave guide section 12. As before, coaxial line section 15 is inserted therein and may be longitudinally positioned by knob 61.

It is thus seen that the present invention provides a mode transformer for coupling a rectangular wave guide to a circular wave guide, the two guides being in axial alignment. The invention further provides a structure for coupling the TE₁₀ in the rectangular guide to a circular polarized wave of the TE₁₁ mode in a circular wave guide. Still further, the present invention provides an axially aligned mode transformer which is capable of operating efficiently over a range of operating frequencies.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. An electromagnetic wave energy mode transformer comprising a section of rectangular waveguide, a section of circular waveguide, said waveguide sections having

wave energy propagation axes in substantial alignment, means for coupling wave energy directly between said waveguide sections, a section of coaxial transmission line extending through said means and having one end portion thereof extending within said rectangular waveguide section and having the other end portion thereof extending within said circular waveguide section, and wave energy pick-ups terminating the ends of said coaxial line section and oriented to couple said coaxial line section to said circular waveguide section with a fundamental transverse electric wave energy mode having its electric field vector in quadrature relative to the electric field vector of the wave energy field in said waveguide section, whereby the wave energy phase transitions provided by said coupled waveguide sections, said means, and said coaxial line section cooperate with said oriented pick-ups to maintain a wave energy mode transformation between a transverse electric wave energy mode in said rectangular section and a circular-polarized fundamental transverse electric wave energy mode in said circular waveguide section.

2. An electromagnetic wave energy mode transformer comprising a continuous length of hollow wave guide having a central longitudinal axis of propagation, a first portion of said wave guide being rectangular in cross-section and a second portion of said wave guide having a circular cross-section, a transmission line positioned within said wave guide along said axis of propagation, means for supporting said line, and energy pick-up and radiating means terminating each end of the transmission line, the ends of the transmission line terminating respectively in the rectangular and circular portions of the wave guide.

3. An electromagnetic wave energy mode transformer as described in claim 2 wherein said transmission line is a coaxial line section.

4. An electromagnetic wave energy mode transformer as described in claim 3 wherein said energy pick-up and radiating means is a dipole element, the dipoles at each end of the coaxial line section being oriented at substantially 90° with respect to each other.

5. Apparatus as defined in claim 4 wherein the means for supporting the coaxial line is adjustable longitudinally of the wave guide.

6. Apparatus as defined in claim 2 wherein said wave guide includes a portion of wave guide intermediate said circular and rectangular portions.

7. Apparatus as defined in claim 6 wherein said intermediate portion is rectangular and substantially larger in cross-sectional dimensions than the first-mentioned rectangular portion but not larger in any cross-sectional dimension than the diameter of said circular portion.

8. Apparatus as defined in claim 7 wherein a tapered line section joins said intermediate portion and said first-mentioned rectangular portion of the wave guide.

9. Apparatus as defined in claim 6 wherein said intermediate portion is a rectangular-to-circular wave guide transition section.

10. An electromagnetic wave energy mode transformer comprising a continuous length of hollow wave guide having a central longitudinal axis of propagation, a length of transmission line positioned within the wave guide along said axis, and energy pickup and radiating means terminating each end of the transmission line whereby a portion of the energy transmitted along the wave guide is carried by the transmission line, the length of the transmission line being such as to effect a quadrature phase difference between the portion of energy propagated directly by the wave guide and the portion of energy propagated by the transmission line, the pickup and radiating means at one end of the transmission line being oriented at ninety degrees relative to the pickup and radiating means at the other end of the transmission line whereby the plane of the E-vector of the energy radiated at one end of the transmission line is rotated ninety degrees with respect to the

70
75

energy picked up at the other end of the transmission line.

11. An electromagnetic wave energy mode transformer comprising a continuous length of hollow wave guide having a central longitudinal axis of propagation, a first portion of the wave guide being rectangular in cross-section and a second portion of the wave guide being circular in cross-section, a length of transmission line having the ends thereof positioned respectively in the rectangular and circular portions of the wave guide, and energy pickup and radiating means terminating each end of the transmission line whereby a portion of the energy transmitted along the wave guide is carried by the transmission line, the length of the transmission line being such as to effect a quadrature phase difference between the portion of energy propagated directly by the wave guide and the portion of energy propagated by the transmission line, the energy pickup and radiating means at one end of the transmission line being oriented at 90 degrees relative to the energy pickup and radiating means at the other end of the

transmission line whereby the plane of the E-vector of the energy radiated at one end of the transmission line is rotated 90 degrees with respect to the energy picked up at the other end of the transmission line.
